US0D1081596S

(12) **United States Design Patent** (10) **Patent No.:** **US D1,081,596 S**
Chen (45) **Date of Patent:** **** Jul. 1, 2025**

(54) **4 GANG SWITCH PANEL**

(71) Applicant: **Guangzhou Xuntu Network Technology Co., Ltd.**, Guangzhou (CN)
(72) Inventor: **Xiaofeng Chen**, Guangzhou (CN)
(73) Assignee: **Guangzhou Xuntu Network Technology Co., Ltd.**, Guangzhou (CN)

(**) Term: **15 Years**

(21) Appl. No.: **29/984,152**

(22) Filed: **Jan. 14, 2025**

(51) **LOC (15) Cl.** **13-03**
(52) **U.S. Cl.**

USPC **D13/158; D13/164**

(57) **CLAIM**

The ornamental design for a 4 gang switch panel, as shown and described.

DESCRIPTION

FIG. 1 is a front, right and top perspective view of a 4 gang switch panel, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the 4 gang switch panel that form no part of the claimed design.

1 Claim, 8 Drawing Sheets
